RAILWAY SWITCH CIRCUIT CONTROLLER

Herbert L. Bone, Forest Hills, Pa., assignor to The Union Switch & Signal Company, Swissvale, Pa., a corporation of Pennsylvania

Application May 27, 1944, Serial No. 537,584

4 Claims. (Cl. 246—253)

My invention relates to railway switch circuit controllers, and particularly to circuit controllers for use in connection with spring switches of the type which are provided with a facing point lock so constructed that when the switch points occupy their normal positions the locking plunger of the lock will normally occupy a locking position in which it positively locks the switch points in their normal positions, but that, when a train trails the switch the locking plunger will be automatically withdrawn from its locking position to unlock the switch by means mechanically actuated by the train, and that when the movable rails have been returned to their normal positions upon completion of the trailing movement, the locking plunger will be automatically restored to its locking position by spring means to relock the switch.

In one well known form of circuit controller of the type described the same set of contacts are controlled jointly by a point detector rod and by the locking plunger in such manner that these contacts will be operated either by displacement of the switch points from their normal positions or by displacement of the locking plunger in either direction from its normal locking position. These contacts have usually been employed to control both the main line and siding signals for the switch, and with this arrangement it occasionally happens that main line trains are compelled to stop due to movement of the locking plunger beyond its normal locking position (overtravel), whereas the only movements of traffic over the switch which might be adversely affected by the overtravel of the plunger are trailing moves since the overtravel does not cause a dangerous condition for main line traffic but only makes it impossible for a trailing train to unlock the switch. This is undesirable, and the principal object of my invention is to provide means whereby circuit controllers of the type described may be constructed to give an indication for plunger overtravel separate from that for the normal position of the points and for undertravel of the locking plunger. The overtravel indication may then be used to control the siding signal only and the other indication may be used to control the main line signals only with the result that main line traffic will not be penalized by overtravel of the locking plunger and trailing trains will not be penalized by any condition except that which makes it impossible for these trains to unlock the switch.

According to my invention, I modify the cam dog which is carried by the locking plunger of the

usual spring switch circuit controller, and which heretofore has been provided with means for operating the main contacts of the controller in response to either overtravel or undertravel of the plunger, so that this dog is now effective to operate these contacts when and only when the locking plunger is moved more than a predetermined distance from its proper locking position toward its unlocking position, and I provide the controller with means for operating the contacts which heretofore have been provided for reverse point detection in response to overtravel of the plunger. These latter means consist of an overtravel spring plunger assembly actuated by the locking plunger and cooperating with a cam provided on the member which heretofore functioned with the point detector rod to operate the reverse point detector contacts.

Other objects and characteristic features of my invention will become apparent as the description proceeds.

I shall describe one form of circuit controller embodying my invention, and shall then point out the novel features thereof in claims.

In the accompanying drawings, Fig. 1 is a top plan view showing a spring switch A operated by a switch operating mechanism B provided with a circuit controller embodying my invention. Fig. 2 is an enlarged top plan view of the circuit controller of the mechanism shown in Fig. 1 with the cover removed to show the operating parts thereof. Fig. 3 is a vertical longitudinal sectional view of the circuit controller embodying my invention. Fig. 4 is a sectional view taken substantially on the line IV—IV of Fig. 3. Fig. 5 is a detail sectional view of a part of the circuit controller shown in the preceding views. Figs. 6, 7 and 8 are detail views of various parts of the circuit controller shown in the preceding views.

Similar reference characters refer to similar parts in each of the several views.

Referring first to Fig. 1, the reference character A designates a railway switch comprising as usual two fixed rails 1 and 1a and two movable rails 2 and 2a. The fixed rails 1 and 1a are laid on tie plates 3 and are secured to crossties 4 in the usual manner. The movable rails 2 and 2a are fastened together by a front rod 5, a head rod 6, a bridle rod 7 and a tie rod 8, and may be moved into a normal or a reverse position by means of a switch operating mechanism B which is connected with the head rod 6 through the medium of an operating rod 9 and a spring connecting rod C. When the switch occupies its normal position in which position it is shown in

Fig. 1, the movable rail 2 engages the fixed rail 1, and the movable rail 2a is spaced from the fixed rail 1a. When the switch is reversed, however, the movable rail 2a then engages the fixed rail 1a, and the movable rail 2 is spaced from the fixed rail 1.

The spring connecting rod C may be of any suitable type, but in the well known form here illustrated, this connecting rod is similar in all respects to the spring connecting rod C shown and described in Letters Patent of the United States No. 1,976,827, granted to me on October 16, 1934, for Railway switch operating apparatus. It is believed, therefore, that for purposes of my present disclosure it is sufficient to point out that this connecting rod includes spring means which biases the switch points to whichever extreme position they are moved to by the mechanism B with sufficient force to permit facing point moves over the switch without displacement of the points, but which yields when a train trails the switch and thereby allows the train to force the switch points to a position opposite to that to which they are biased by the spring means.

The head rod 6 is also connected by means of an adjustable jaw 15 with the piston rod 16 of a buffering device D. This buffering device may also be of any suitable type but, as here shown, this buffering device is similar in all respects to the buffering device shown and described in Letters Patent of the United States No. 1,869,604, granted to William C. McWhirter on August 2, 1932, for Buffering devices for railway switches and the like. It is believed, therefore, that a detail description of this device is unnecessary. It should be pointed out, however, that this buffering device includes, in addition to the piston rod 16, a cam shaft 17 extending into the case of the device and controlling a valve mechanism not shown. Attached to the outer end of the cam shaft 17 is a crank 18 which is connected by a link 19 with the spring rod 14 of the spring connecting rod C. If when the movable rails 2 and 2a of the switch A are in their normal positions, as shown in Fig. 1, they are moved to their reverse positions by the mechanism B, the piston rod 16 will be moved into the device and the cam shaft 17 will be rotated in a clockwise direction, as viewed in Fig. 1. The construction of the device is such that, under these conditions, the piston rod 16 will be permitted to move with substantially no resistance, and the buffering device will therefore exert practically no retarding action on the movable rails. Conversely, if the movable rails are moved from their reverse positions to their normal positions by the mechanism B, the piston rod 16 will be moved outwardly and the cam shaft 17 will be rotated in a counter-clockwise direction, as viewed in Fig. 1, but due to the construction of the device, no retarding action will again take place. If, however, when the movable rails are in either extreme position, a train trails the switch, the cam shaft 17 will remain stationary, and under these conditions, the action of the device is such that the movement of the movable rails away from the positions which they previously occupied will be unresisted by the buffering device, but that, when the movable rails are being restored to the positions which they previously occupied by the spring means of the spring connecting rod C, the buffering device will act to retard this latter movement.

The switch operating member B is mounted on one end of a tie strap 20 which is secured to the ties adjacent the outer side of the rail 1, and as

here shown is similar in all respects to that described and claimed in Letters Patent of the United States No. 2,235,031, granted to Kenneth J. J. McGowan on March 18, 1941, for Railway switch operating apparatus. Since the construction of the mechanism is described in detail in the said McGowan patent, it is believed to be sufficient for the purpose of my present application to point out that this mechanism includes a hand throw lever 21 connected with a switch operating crank 22 through suitable operating mechanism not shown in such manner that the operating crank will occupy the normal extreme position shown or will be rotated from this position in a counterclockwise direction to a reverse extreme position according as the hand throw lever occupies the position shown or its opposite extreme position. The switch operating crank 20 is operatively connected with the previously described operating rod 9.

The mechanism B also includes a locking plunger 23 which cooperates with a notch 24 in a lock rod L to at times lock the switch in its normal position for facing point moves over the switch. When the hand throw lever 21 occupies the position shown, the locking plunger is yieldably biased by spring means 25 to a locking position in which it is disposed in the notch 24 in the lock rod L, and under these conditions the switch is locked, but when the hand throw lever is rotated from the position shown toward the opposite extreme position, the locking plunger is withdrawn from the notch 24 to unlock the switch before any movement of the switch operating crank 22 takes place.

The lock rod L is slidably mounted in a transverse guideway formed in the casing of the mechanism B, and is adjustably secured at one end to the front rod 5 of the switch A. The notch 24 is so disposed that it will align with the locking plunger 23 when and only when the switch A occupies the extreme position in which it is shown in the drawings and the movable rail 2 is in proper engagement with the fixed rail 1.

The parts of the mechanism B are so proportioned that when the hand throw lever 21 occupies its normal position as shown, the spring means 25 which moves the locking plunger 23 to its locking position will tend to drive the locking plunger beyond the desired locking position. The locking plunger is prevented from moving beyond the desired locking position under these conditions, however, by linkage 26 which connects it with the tie rod 8. The linkage 26 also constitutes means for moving the locking plunger 24 to its unlocking position to unlock the switch when a train trails the switch as is fully explained in the aforementioned McGowan Patent No. 2,235,031.

Located in the lower end of the casing 30 of the mechanism B is a circuit controller E comprising a rocker arm 31 pivotally supported intermediate its ends on a pivot pin 32 mounted in a pair of spaced lugs 33 extending upwardly from the bottom of the casing 30. The rocker arm is disposed directly above the locking plunger 23, and is provided with a roller 34 and with a cam face 35, which roller and cam face cooperate, in a manner which will be made clear presently, with a cam dog 36 secured to the upper side of the locking plunger. Pivotally attached to the left-hand end of the rocker arm 31 is a contact operating member 37. This contact operating member is mounted to move vertically on guide studs 38, and is biased to an upper position by compressed coil springs 47 disposed on the studs 38. Secured to

the upper side of the contact operating member are two superposed blocks 39 and 40 of insulating material between which are clamped the free ends of a plurality of flexible contact fingers 41 here shown as four in number. Each contact finger 41 cooperates with an associated contact member 42 to form a plunger lock contact 41-42. Each contact finger 41 and the associated contact member 42 are clamped to the opposite sides of an insulating block 43 by means of terminal posts 44 and 45, and the insulating block 43, in turn, is supported on legs 46 provided on a supporting bracket 48. Each terminal post 44 is electrically connected with the associated contact member 42 but is insulated from the associated contact finger 41, while each terminal post 45 is electrically connected with the associated contact finger 41 but is insulated from the associated contact member 42.

The cam dog 36 is provided with a cutaway portion 36a which aligns with the roller 34 when the locking plunger 23 is moved to its full locking position or to any position beyond this position, and the parts are so proportioned that when this cutaway portion is in alignment with the roller the contact operating member is free to move due to its bias to its upper position in which the contacts 41-42 are open. When, however, the locking plunger is moved to its unlocking position the high portion of the cam dog 36 engages the roller 34 before the plunger has been moved far enough to clear the lock rod and rotates rocker arm 31 counterclockwise about the pivot pin 32. This rotation of the rocker arm forces the contact operating member 37 downwardly in opposition to the bias of the springs 47, and thus closes the contacts 41-42. When the locking plunger has been withdrawn its full travel, the cam dog 36 will have moved beyond the roller 34, but the rocker arm will be held in its counterclockwise extreme position under these conditions by engagement of the cam face 35 with the top of the cam dog. It will be apparent, therefore, that the plunger lock contacts will be open when the locking plunger is in its locking position or any position beyond this position but will be closed when the plunger occupies its unlocking position or any position between its unlocking and its locking position.

The circuit controller also comprises a point detector lever 50 (Fig. 7) which is pivotally supported on pins 51 mounted in the bracket 48, and which is biased, by means of a spring 52 interposed between the frame and a laterally projecting arm 53, in a counterclockwise direction to the position in which a roller 54 mounted in a depending lug 55 (see Fig. 7) formed on the point detector lever enters a notch 56 in a point detector rod P. The point detector rod P is slidably mounted in the casing 30, and as shown in Fig. 1 is attached by means of a link 57 and a bolt 58 to the movable rail 2 of the switch A in the usual and well-known manner. The point detector lever 50 is also provided with a laterally projecting arm 59 having a rounded end which overlies and cooperates with the conical head 60a of a finger 60 which is adjustably mounted in the end of the rocker arm 31. The notch 56 in the point detector rod P is so disposed and the parts are so proportioned that the roller 54 will enter the notch 56 when and only when the movable rails 2 and 2a of the switch A occupy their normal extreme positions and the movable rail 2 is in proper engagement with the movable rail 1. The parts are further

so proportioned that when the roller 54 is within the notch 56 and the rocker arm 31 occupies its normal position, the rounded end of the arm 59 will just touch the upper side of the conical head 60a of the finger 60, but that, when the roller 54 is forced out of the notch 56, the resultant clockwise rotation of the point detector lever 50 will cause the rounded end of the arm 59 to cooperate with the head 60a of the finger 60 in a manner to rotate the rocker arm 31 to its counterclockwise or reverse extreme position, thus causing the contacts 41-42 to become closed. It follows, therefore, that any displacement of the switch point 2 away from the rail 1 when the parts are in the positions shown in the drawings will operate the contacts 41-42.

The portion of the circuit controller thus far described is identical to circuit controllers which are in widespread use except for the fact that the cam dog 36 has been modified so that movement of the locking plunger beyond the desired locking position (overtravel) will not cause operation of the contacts 41-42. As was pointed out hereinbefore, the object of my present invention is to provide means whereby overtravel of the locking plunger will provide an indication which is wholly independent of the indication provided by the portion of the circuit controller thus far described, and I accomplish this object by the novel means which I shall now describe.

As here shown, these means comprise a second set of contacts, each comprising a flexible contact finger 65 cooperating with a fixed contact member 66. Each flexible contact finger 65 is fastened at one end to a conducting strip 67, the other end of which is clamped against the lower side of an insulating terminal board 68 by means of a terminal post 69 which is electrically connected with the strip and a terminal post 70 which is insulated from the strip, while each fixed contact member 66 is secured to, and electrically connected with, an associated one of the terminal posts 70. The terminal board 68 is secured at its ends to the supporting bracket 48. Pivotally mounted below the contact fingers 65 on the same pivot pins 51 which support the point detector lever 50 is a contact operating member 71 provided with an insulating block 72 which cooperates with the flexible contact fingers 65 in a manner which will be made clear presently. The contact operating member 71 is also provided with a laterally projecting cam lug 73, and is biased in a counterclockwise direction as viewed in Fig. 3, by means of a spring 74 to a position in which the cam lug 73 engages a cam head 75 screwed onto the end of a spring rod 76 forming part of a plunger overtravel spring assembly. The spring 74 is stretched between a spring lug 77 (see Fig. 4) formed on the contact operating member 71 and a spring bracket 78 secured to the bottom of the mechanism casing. The spring rod 76 is slidably mounted in spaced guideways 79 and 80 provided in a supporting frame 81, and is surrounded between the guideway 79 and a washer 82 which abuts against a shoulder 83 formed on the rod, by a compressed coil spring 84 which biases the spring rod toward the right, as viewed in Fig. 3. The supporting frame 81 is clamped by means of machine screws 85 (see Figs. 4 and 5) against finished pads 86 provided on the underside of the supporting bracket 48 in such position that the spring rod 76 aligns axially with the locking plunger, and the parts are so proportioned that when the locking plunger occupies its normal locking position it will be out of engagement with

the spring rod, but that, if overtravel of the locking plunger occurs for any reason, the end of the locking plunger will then engage the adjacent end of the spring rod and will move it toward the left as viewed in Fig. 3. The limit of overtravel of the locking plunger is determined by engagement of the cam dog 36 with a strut 89 on frame 48, and the parts are further so proportioned that if overtravel of the plunger occurs, the cam head 75 carried by the operating rod will cooperate with the cam lug 73 to rotate the contact operating member 71 in a clockwise direction in opposition to the bias of the spring 74, to a position in which the insulating block cooperates with the flexible finger 65 to operate the contacts 65-66.

It will be seen from the foregoing that in accordance with my present invention the circuit controller is provided with two separate and independent sets of contacts, one set of which is operated either by displacement of the switch points away from their normal set positions or by movement of the locking plunger from its normal locking position toward its unlocking position, and the other set of which is operated by overtravel of the locking plunger. The provision of these two sets of contacts enables the main line and siding signals commonly employed in connection with spring switches to be separately controlled in such manner that main line traffic will not be penalized by overtravel of the locking plunger, and trailing trains will not be penalized by any condition except that which makes it impossible for these trains to unlock the switch.

It should be particularly pointed out that the contacts 65-66 may be identical with those which are commonly provided for detecting that the switch points are in their proper positions relative to the stock rails when they are set in these positions by operation of the mechanism B to its reverse extreme position, and that the contact operating member 71 is also identical with that which is commonly used to provide reverse point detection except for the addition to this bracket of the cam lug 73. It follows, therefore, that in order to convert a circuit controller of the type heretofore in widespread use into one embodying my present invention it is only necessary to modify the cam dog 36 in the manner outlined hereinbefore, replace the usual contact operating member 71 by one provided with a cam lug 73, and add the overtravel spring plunger assembly to the mechanism.

Although I have herein shown and described only one form of circuit controller embodying my invention, it is understood that various changes and modifications may be made therein within the scope of the appended claims without departing from the spirit and scope of my invention.

Having thus described my invention, what I claim is:

1. In combination, a railway switch, a lock rod connected to said switch to move therewith and provided with a notch, a locking plunger normally movable between a locking position in which said plunger is within said notch and an unlocking position in which it is withdrawn from said notch but capable of abnormal movement within said notch past said locking position, a contact, and means for detecting said abnormal movement comprising a spring rod biased to a position to be operated by movement of said plunger beyond its locking position, and cam means operatively connecting said contact with said spring rod.

2. In combination, a spring switch, a lock rod connected with said switch and provided with a notch, a locking plunger normally movable between a locking position in which said plunger is within said notch and an unlocking position in which it is withdrawn from said notch, means biasing said plunger past its locking position within said notch, linkage actuated by a train trailing said switch and connected with said plunger for moving said plunger to its unlocking position, said linkage normally being effective to prevent movement of said plunger beyond its locking position within said notch, a contact, and means for detecting movement of said plunger beyond its locking position comprising a spring rod disposed adjacent the end of said plunger and biased to a position to be moved in opposition to its bias by movement of said plunger beyond its locking position, and means operatively connecting said spring rod with said contact.

3. In combination, a spring switch, a lock rod connected with the switch points to move therewith and provided with a notch, a locking plunger adapted to enter the notch in said lock rod when and only when the switch occupies its normal extreme position, said locking plunger being movable within said notch to an extreme position which is beyond its normal locking position, means for moving said locking plunger into and out of engagement with said notch, a cam dog secured to said locking plunger, a pivoted rocker arm provided with means cooperating with said cam dog in such manner that when said locking plunger occupies its locking position or any position beyond this position said rocker arm will be rotated to one extreme position but that if said locking plunger is withdrawn from its locking position said rocker arm will be rotated to another extreme position, a first contact operated by said rocker arm, a locking plunger overtravel spring assembly mounted adjacent the end of said plunger and comprising a spring rod biased to a position to be operated by movement of said locking plunger beyond its locking position, a cam head secured to said spring rod, a contact operating member provided with a cam lug cooperating with said cam head in such manner that movement of said spring rod by engagement with said locking plunger will operate said contact operating member, and a second contact operated by operation of said contact operating member.

4. In combination, a railway switch, a lock rod connected to the switch to move therewith and provided with a notch, a locking plunger normally movable between an unlocking position in which it is out of engagement with said lock rod and a locking position in which it enters said notch but capable of abnormal movement within said notch past its locking position, a first contact, cam means cooperating with said first contact for operating said contact to one or another position according as said locking plunger occupies its locking position or is moved away from its locking position toward its unlocking position, and means for detecting abnormal movement of said plunger beyond its locking position comprising a second contact, a spring rod biased to a position to be operated by movement of said plunger beyond its locking position, and cam means operated by said plunger for operating said contact.

HERBERT L. BONE.
